UNITED STATES PATENT OFFICE.

CHARLES WARREN, OF GUELPH, CANADA, ASSIGNOR, BY MESNE ASSIGNMENTS, TO ARTIST PIANO PLAYER COMPANY, A CORPORATION OF MICHIGAN.

PIANO-PLAYER.

SPECIFICATION forming part of Letters Patent No. 769,852, dated September 13, 1904.

Application filed February 8, 1904. Serial No. 192,616. (No model.)

To all whom it may concern:

Be it known that I, CHARLES WARREN, of the city of Guelph, in the county of Wellington, in the Province of Ontario, Canada, have 5 invented certain new and useful Improvements in Piano-Players, of which the following is a specification.

My invention relates to improvements in piano-players; and the object of the invention 10 is to provide a simple means whereby pianissimo or fortissimo changes may be produced independent of either the treble or bass of the piano, or in both together, whereby space may be economized in the operative parts by which 15 such effects are produced, and whereby the operation of exhausting may be performed more quickly, and consequently the effects produced more quickly; and it consists, essentially, of two separate exhaust-reservoirs 20 located one toward each end underneath the pneumatic - chamber and independent exhausters each separately attached to its own exhaust-reservoir and connected by a rod to its pedal, the parts being otherwise constructed and arranged in detail as hereinafter more particularly explained.

Figure 1 is a perspective view of the main portion of the frame of a piano-player, the outer portion of the casing being removed to 25 exhibit the interior construction. Fig. 2 is a longitudinal section through the parts involved in my invention.

In the drawings like characters of reference indicate corresponding parts in each figure. 30 A is the pneumatic-chamber, which is preferably divided by partitions *a a* into two portions, and B and B' are the trunks leading to each portion. In the horizontal portion of the trunks B and B', I provide the orifices *b* 35 and *b'*, which are controlled by the slide-valves 2 and 3, connected by the bars 2' and 3' to the bell-cranks 4 and 5, journaled in the bracket *c* on the bottom board C. The ends of the bell-cranks 4 and 5 have connected to 40 them the push-plungers 4' and 5', the tops of which are provided with the usual stop-heads and are situated in front of the tracker-board, as indicated.

D and D' are exhaust-reservoirs provided with the usual expansion-springs *d* and *d'* and 50 valves *d²* and *d³*. The exhaust-reservoirs D and D' are located one at each side of the player underneath the board and are connected together by a small by-pass 6.

E and E' are the exhausters, which are provided with the usual flap-valves *e* and *e'* and the springs *e²* and *e³*. The ends of the exhausters E' are connected by the rods 7 7' to the pedals 8 and 8', respectively.

It will be seen by the construction that I 60 have described that I economize a great deal of space by dispensing with the ordinary large reservoir, and, further, each pedal has its controlling power for both the bass and treble 65 ends of the player.

I make a division in the pneumatic-chamber at any given point, as at *a a*. By this it is evident if I wish to produce fortissimo at the base or treble ends, or conversely, it can be produced by the pedals, and this is further 70 accelerated by employing two exhaust-trunks B and B', as hereinbefore described, each being provided with a separate cut-off valve controlled as described to give a variable exhaust as required by the operator. I also 75 have provided, as hereinbefore described, the by-pass 6 between the two reservoirs D and D', and by this I am enabled to produce a partial vacuum for either base or treble, as desired.

It will thus be seen that I have provided 80 perfect control over the pneumatic-chambers, and consequently the pneumatics, and am enabled to produce effects which have heretofore been impossible in piano-players of this 85 description.

What I claim as my invention is—

1. In a piano-player, the combination with a divided pneumatic-chamber, of the independent trunks connected thereto and having orifices, suitable controlling-valves for the orifices, and independent exhaust-reservoirs communicating with each trunk, and exhausters for each reservoir, and means for operating the exhausters as and for the purpose specified. 90

2. In a piano-player, the combination with 95

a divided pneumatic-chamber, of the independent trunks connected thereto and having orifices, suitable controlling-valves for the orifices, and independent exhaust-reservoirs communicating with each trunk, and exhausters for each reservoir, the pedals, the rods connecting the ends of the exhausters to the ends of the pedals as and for the purpose specified.

3. In a piano-player, the combination with 10 a divided pneumatic-chamber, of the independent trunks connected thereto and having orifices, suitable controlling-valves for the orifices, and independent exhaust-reservoirs communicating with each trunk, and exhausters 15 for each reservoir, means for operating the exhausters, and a by-pass extending between the exhaust-reservoirs as and for the purpose specified.

4. In a piano-player, the combination with 20 a divided pneumatic-chamber, of the independent trunks connected thereto and having orifices, suitable controlling-valves for the orifices, rods connected to the valves above the

bellows-board, bars connected to the ends of the rods above the bellows-board, bell-cranks 25 connected at one end to the ends of the bars and push-plungers connected to the other ends of the bell-cranks and extending up through the tracker-board frame as and for the purpose specified.

5. The combination with a pneumatic-chamber having a divisional partition and the trunks L shape in form and provided with orifices, valves to control such orifices, the bellows-board extending underneath the trunks 35 and provided with an orifice communicating with the orifice in the trunks, the independent exhaust-reservoirs provided with suitable valves and independent exhausters located directly underneath the exhaust-reservoirs and 40 means for operating the exhausters as and for the purpose specified.

CHARLES WARREN.
